United States Patent Office

Des. 198,732
Patented July 21, 1964

198,732

ROTATABLE DISPLAY STAND OR SIMILAR ARTICLE

Ernest L. Shapiro, Morton Grove, Ill., assignor to Alberto-Culver Company, Melrose Park, Ill., a corporation of Delaware

Filed Dec. 20, 1963, Ser. No. 77,877

Term of patent 14 years

(Cl. D80—9)

FIG 6

FIG 1

Des. 198,732

PAGE 2

FIG - 2

FIG - 3

FIGURE 1 is a perspective view of a rotatable display stand, or similar article, showing my new design;
FIGURE 2 is a front elevational view thereof;
FIGURE 3 is a right side elevational view thereof;
FIGURE 4 is a rear elevational view thereof;
FIGURE 5 is a top plan view thereof; and
FIGURE 6 is a bottom plan view thereof.

I claim:

The ornamental design for a rotatable display stand or similar article, as shown.
